UNITED STATES PATENT OFFICE.

THEODORE W. MUCKLE, OF DENVER, COLORADO.

METHOD OF AND FURNACE FOR MELTING METALLIC MASSES.

1,363,188.

Specification of Letters Patent. Patented Dec. 21, 1920.

Application filed April 22, 1919. Serial No. 291,934.

To all whom it may concern:

Be it known that I, THEODORE W. MUCKLE, a citizen of the United States, residing at the city and county of Denver and State of Colorado, have invented a certain new and useful Method of and Furnace for Melting Metallic Masses; and I do hereby declare the following to be a full, clear, and exact description of the invention, such as will enable others skilled in the art to which it appertains to make and use the same.

This invention relates to the art of melting metallic masses, and embodies both a novel method of reduction as well as an improved type of furnace construction for more expeditiously and expeditiously carrying forward the steps thereof.

The objects and advantages of the same will be so clearly apparent, as incidental to the following complete disclosure, that it would only be undesirable surplausage to initially refer to them, and as it is believed that a better conception thereof, and of the distinguishing features over the prior art as understood, may be had after a more thorough understanding of the improved furnace itself, it is deemed more expedient to first generally describe the latter.

Before doing so, however, it may not be amiss to state that while the actual method involved may doubtless be performed with other types of furnaces, which are suitably equipped and adapted for the purpose, and that the furnace may likewise be employed in relations other than with the particular method for which it has primarily been designed, still the two are so inseparably allied, in broader aspects, as to be fairly considered of substantially one and the same identity.

With these prefacing remarks, therefore, reference shall immediately be had to the accompanying drawings, forming a part of this specification, in which drawings—

Figure 1 is a vertical cross-sectional view of the improved furnace, taken along the line 1—1 of Fig. 3; Fig. 2 is a local sectional view through the arched top wall of the furnace body and one of the removable bungs, associated therewith for charging purposes, as shown in side elevation in Fig. 1, the section being taken between abutting faces of a pair of the bricks of said removable bung disposed adjacent to the central truss-bearing and lifting support therefor; and Fig. 3 is a front elevational view of a

furnace employing a series of four heating units.

8 designates the front wall of the furnace body and 9 the rear wall thereof, while the actual foundation base is not shown but is represented by its covering of silica sand indicated at 10. The rear wall is of substantially less height than the front wall, and both of these walls, as well as the foundation base, may be built up of any suitable refractory material, such as the usually employed fire clay bricks or blocks.

Either the rear wall or the end walls of the furnace, or both rear and end walls thereof, are provided with slag openings 11, disposed adjacent the approximate metal line, and these openings are preferably formed, as shown, with the inclined bottom face 12 and the horizontal shelf-like face 13, which permits the operative to more facilely skim off or drag out any dross matter accumulating on the liquid surface of the fusing metallic mass. These openings are controlled by any suitable doors or closures, conventionally illustrated by a refractory plug 14.

Also, any suitable tapping outlets may be provided in either one or more of the walls, but this has simply been illustrated by a single tap-bore 15, leading from near the bottom of the melting chamber, through the front wall 8, and discharging into a trough or delivery spout 16. Obviously this tap-bore 15 is controlled by the usual plugging means.

17 designates a flame inlet opening or passageway through the front wall 8, toward the upper end thereof, the side faces of which are preferably flared inwardly, as indicated at 18, to provide a laterally divergent delivery opening for spreading out the entering fuel mixture, or flame upon ignition, which is introduced into the melting chamber in the nature of a substantial blast.

As many of these inlets may be employed as the length of the furnace and the practically unlimited scale of operations may require, but for each one thereof the melting chamber is furnished with dually arranged exits for conducting off the gaseous formations and products of combustion from the spent blasts. These exits may be located at any suitable positions relatively to the front wall of the melting chamber, provided that one at least is disposed in a plane at each

side of each inlet opening. Thus the exits coöperate in pairs to exhaust the said products of combustion and gaseous formations, from each blast flame, independently of the 5 other operating blasts; and in actual effect this will serially divide up the unobstructed and otherwise uninterrupted melting chamber, establishing and maintaining a distinctly defined heating zone for each blast 10 flame, but which collectively co-act in the melting of the metal *en masse*. The material importance of this distinctive step will more fully hereinafter appear.

A satisfactory expedient toward this important end has been found in the provision 15 of the pairs of flues 19 and 20, extending through the front wall 8, one on each side of the vertical plane of its own particular inlet opening 17, although further experimentation may demonstrate that a single 20 flue intermediate of the flame openings might suffice, providing they coöperate in pairs relative to any particular inlet opening. Also, the flues 19 and 20 may pass on 25 up through the front wall as shown, exhausting at the top thereof, although obviously this arrangement may be otherwise, and in any event expensive chimney constructions are wholly avoided. The lower 30 ends of the flues may open into the melting chamber near its bottom, as at 21, and the bottom walls thereof are preferably disposed at an incline, as at 22, so that as the molten mass is tapped off, none of it will remain 35 lodged in the bottom of the flues.

The top wall of the melting chamber is in the form of a substantial arch 23, built up of refractory material such as fire clay sections or bricks. The major portion of the top wall 40 is preferably of a fixed structure, extending from the front wall 8, immediately above the inlet openings 17, to the top of the rear wall 9; but its length provides for a suitable number of transversely disposed charging 45 openings, in each of which a removable bung is adapted to be snugly seated.

These removable bungs are of the same curvature as the top arched wall 23, and may be formed of any appropriate refractory sections, although preferably built up 50 into a firmly keyed structure of fire clay bricks 24, recessed to provide rabbeted corners and the depending tongue portions 25, and the whole unit serving as a substantial 55 elongated form of plug closure for the transversely disposed charging openings, the tongue portions 25 being of a length to neatly fit said charging openings, while the rabbeted corners provide seating shoulders 60 for resting upon the spaced top surfaces of the fixed arch 23. As this removable bung unit is quite heavy, the tongue portions of the bricks are of considerable less depth than the overhanging upper ledge portions there- 65 of, which have to sustain the load. Also,

as the assembled bricks have to be held compactly against separation from strains and internal pressures, it is desirable that a light metallic support be employed, which will serve both as a keying truss and a handling 70 means therefor, and which will now be described, particular reference being had to Fig. 2 viewed in connection with Fig. 1.

26 designates a centrally disposed base member, having an upwardly projecting 75 apertured lug 27 and a pair of top grooved seats 28, while 29 designates a pair of arched metallic side plates secured centrally to the base member as by bolts 30. The side plates terminate in vertical ears 34, between which a pair of end plates 35 are movably supported, as by being hinged thereto, and these end plates are suitably engaged by the threaded ends and nuts 37 of a pair of divergently bent tie rods 36, the central bent 85 portions of which seat in the grooves 28 of the base member 26.

The upper longitudinal edge faces of the bricks are set against the concave edge faces of the side plates 29, and upon tightening 90 up the nuts 37 the end plates 35 are obviously drawn up against the ends of the row of bricks, binding the same together as a keyed unit by the trussing action of the tie- rods, while the apertured lug of the central base member 26 serves as a ready means for handling the removable bungs by a traveling crane operating longitudinally above the furnace.

For the purpose of convenient reference 100 later, 31 simply designates the inside surfaces of the end walls of the melting chamber, and 32 the inside surface of the front wall, but more particularly the surfaces between the pairs of flues 19 and 20, while 33 105 indicates the deflecting surface of the top wall arch 23. In the end wall of Fig. 1, the slag opening 11 is omitted to permit of a clearer illustration of the path of the hot 110 gases in the melting chamber, but it is understood that such slag openings may be supplied for the end walls, if desired, and as indicated in Fig. 3.

From a broader aspect, it may be found sufficient to introduce blast flames through 115 the inlet openings 17 (or blasts of combustible mixtures immediately convertible into flames, from any suitable sources, such as hydrocarbon burners generally, whether of the gas or oil type, or even from powdered 120 coal burners or the like; but in actual practice it has been determined most expedient to employ an oil burner of the low pressure type, both in point of successful and economical operation.

As will be understood from Fig. 3, these burners are arranged in series, the number employed being only limited by the dimensions of the furnace, and referring to the same conventionally, 40 simply designates 125

a burner casing, 41 its nozzle tip, 42 its needle valve controlling stem, 43 the oil serving conduits therefor, and 44 air supplying branches from the main pressure air conduit 5 45. Obviously the pipe line 43 is fed from any suitable oil supply, while the main air conduit 45 is likewise supplied, with air under a fairly low pressure, from any suitable source, as by means of a rotary blower 10 (not shown) coupled up therewith. Also, each burner may be provided with dampering means, for locally controlling the pressure air delivered to the burner casing, as well as adjustable means for independently 15 regulating the admixture of said pressure air with the fuel oil; but these are rather details of the burner construction, requiring no specific description herein.

The general operation of the improved 20 furnace construction will be fairly apparent from an inspection of Fig. 1, in view of the foregoing description, but as it will probably be made even more comprehensive, from an amplified statement of the method 25 involved herein, I will now proceed in detail with reference to the latter.

In my former Patent #1,286,719 of December 3, 1918, I originally disclosed a particular novel type of furnace for melting 30 metals generally with certain superior results, and a broad feature common to both inventions is my generic idea of so initially introducing a blast flame, into the melting chamber of the furnace, as to first provide 35 for the burning out of all of the oxygen of the flame by its complete combustion, after which the resultant hot gases and products of combustion (in the form of a continuing deoxidized heat blast only and not as a true 40 flame at all, its oxygen being wholly exhausted) are caused to traverse the melting mass in suffused intimate contact therewith, whereby a direct intensive heating thereof is rapidly and economically accomplished 45 without any undue oxidizing effect.

In the instant case I have made still further advances in respect of certain decidedly important particulars, the distinguishing characteristics of which may be 50 more sharply defined by way of comparisons, and which provide not only for improved furnaces of practically unlimited capacities but more important still, the improved method enables me to practically 55 revolutionize, as it were, the highly expensive and time consuming operations heretofore practised in the special industry of producing malleable iron castings—most essential present day factors in the manufacture of agricultural implements, automobile and railway equipment, and various other classes of work subjected to corrosion and shock.

As is well understood, these castings are 60 65 poured from a special quality of cast iron,

of a grade which retains proper constituent values essential to subsequent annealing. Before annealing, the castings are very hard and brittle, the carbon contained then being in the combined form; but during the process of annealing, the oxid of iron yields a portion of its oxygen to the metal which is decarbonized, as most of the combined carbon is eliminated, leaving the remainder in the form of graphitic carbon surrounding 70 the molecules of iron, and thus insuring a final product of tough pliancy.

Therefore, in reducing iron masses for such uses, the poured product must obviously retain approximately all of its carbon in combined form, for if the chemically combined form thereof is destroyed by oxidation, or otherwise burned out of the mass entirely, in the melting operations, then the poured product could not successfully undergo the annealing process, essential to the final production of malleable iron castings.

The advantageous employment of oil burners has long been recognized in metal heating operations generally and even in reductions for malleable iron castings they have actually been tried out, but unsuccessfully so because, by the manner of use then attempted, the carbon in the fusing mass 90 chemically united with the unconsumed oxygen of the contacting flames, while the contained silicon and other values were likewise eliminated, resulting in a pouring product in the nature of gray iron, wholly 95 unsuitable for subsequent annealing. To the best of my knowledge, therefore, the old method of melting with an indirect or reverberated heat, up to the time of my present invention, has been continuously practised in this particular field, although necessitating the costly slow melting operations by the use of coal fires and expensive furnace and chimney construction equipments.

In my own attempts to apply the broader 100 principles of my discoveries, to the reduction of metal for the specific industry of malleable iron castings, on a large scale by the equipment of furnaces of great lengths and comparatively unlimited capacities and 105 with a series of burners discharging into a common melting chamber, I myself encountered further serious obstacles.

The carbon dioxid, forming as the blast 110 flames became consumed, not only would tend to heavily sink toward the melting mass, at the bottom of the furnace chamber, and hang thereover more or less as a stagnated heat dampering or blanketing layer, which 115 was largely overcome, however, by the swirling motion of the hot gases, but more serious still, where the exhaust was provided toward the end of the melting chamber as heretofore, the rapid accumulation of these dense incombustible CO_2 gases would very quickly 120 125 130 135

result in the actual smothering of the incoming flames, extinguishing the burners completely. This would be all the more so true where the actual flames positively impinged 5 upon the melting mass (in furnaces where oxidation was not intended to be avoided) for greater volumes of CO₂ gas would then be formed by the action of the flame on the metallic mass.

10 Finally I devised the method of establishing a practically separate heating zone, for each burner, by conducting off the spent hot products of combustion and all other gaseous formations from that individual burner independently of the others of the series, and this appears to have met all further difficulties.

15 It now remains to set forth the steps of the method in sequential order of operation, 20 it being assumed that suitable charges have been introduced, into the improved furnace shown, by way of the removable-bung closed openings, and that 46 indicates the formation of a silica slag layer, while 47 designates the liquid surface line of the fusing mass.

25 The streams of combustible mixture from the low pressure oil burners 40, being projected through the inlet openings 17, are initially spread out laterally and as ignited 30 masses or blast flames are guided around the surface 33 of the arched top wall, as indicated by the black arrows *a*.

35 Being thus initially directed across the upper space of the melting chamber and downwardly toward the rear wall thereof, substantial complete combustion will have been effected as the resultant hot gases and products of combustion (now converted into a deoxidized heat indicated by the double- 40 tail arrows *b*) are diverted toward the fusing mass below, from whence they are turned and caused (as a continuing blast of deoxidized heat indicated by the single-tail arrows *c*) to traverse the fusing metal, as a 45 bottom confining wall, across toward the front wall of the melting chamber.

50 At this latter position, the main body strikes against the inner surface 32 of the front wall, between the flues 19 and 20, and 55 are caused to swirl upwardly and back again toward the rear of the melting chamber (as indicated by the dotted arrows *b'*) in regenerative relation with the incoming flames *a* and hot gases *b*, whereupon they again 60 traverse the melting mass in a forward direction. There may be several of such successive cycles or swirls before final exit, but in each cycle the incoming volume gradually spreads the outgoing spirally in opposite directions longitudinally of the furnace, until 65 in register with a pair of the exit flues 19 and 20, for that particular burner, through which they are blown out as indicated by the exit arrows *d*.

70 65 During the whole melting operation, the

central zone of the melting chamber is as a vacuous space *e*, and an expansive force is established which causes the deoxygenized blasts to be suffusedly pressed down powerfully upon the liquid surface of the fusing metal, which liquid surface is to a large degree agitated or rifled by the swirling motion of the heat, whereby the heat units are positively impressed right into the surface of the mass, and thus more intimately absorbed by the molecular particles thereof.

75 From the foregoing complete disclosure, it may be summed up that, outside of the direct application of heat, resultant from a series of blast flames, without any undue oxidation occurring, as contradistinguished from an indirect or reverberated heating, satisfactory provision is made for conducting off substantially all of the spent products of combustion and gaseous formations from 80 each separate burner at the extremities of its particular heating zone, insuring proper functioning of the low pressure oil burners employed, and thus especially adapting my novel method, as an economically successful 85 radical departure, to the important industry of producing malleable iron castings of superior quality.

90 What I claim, as new and patentable, is:—

95 1. The method of reducing metals *en masse* in a suitable melting chamber, which includes the steps of so projecting a series of blast flames into said chamber as to permit of their complete combustion initially, after which the continuing blasts of resultant hot gases and products of combustion, as now converted into deoxidized heat, are caused to forwardly traverse the melting mass, in suffused intimate contact therewith, and are thence conducted upwardly 105 into entrained regenerative association with their complementary incoming flame blast, and finally exhausting the spent products of combustion and gaseous formations.

110 2. The method of reducing metals *en masse* in a suitable melting chamber, which includes the steps of so projecting a series of blast flames initially across the top and downwardly of the combustion space thereof as to allow for substantially complete 115 combustion before contact with the metallic mass below, after which the continuing blasts of resultant hot gases and products of combustion, as now converted into deoxidized heat, are caused to forwardly traverse the melting mass with a swirling motion bringing them back into entrained regenerative association with their complementary incoming flame blast, and finally exhausting substantially all of the spent 120 gases and products of combustion of each separate flame at the extremities of its particular heating zone.

125 3. A reduction furnace embodying an elongated chamber providing a lower melt- 130

- ing space and an upper combustion space, with a series of inlet openings for the latter proximate its forward top wall; in combination with means associated with said inlet openings for projecting a series of blast flames across said upper space toward its rear wall, to allow for the substantially complete combustion of said flames before striking the fusing mass in the lower space, 5 let openings for projecting a series of blast flames across said upper space toward its rear wall, to allow for the substantially complete combustion of said flames before striking the fusing mass in the lower space, 10 the top and rear walls of said combustion space serving to divert and direct the continuing resultant blasts of deoxidized heat forwardly across the melting mass in suffused intimate contact therewith; and a 15 series of outlets leading through said front wall from the lower portion of said chamber, which outlets are positioned at each side of the vertical planes of said inlet openings and coöperate in pairs to exhaust the 20 residue products of combustion from each separate blast flame at the extremities of their individual heating zones, substantially as described.
4. A reduction furnace, embodying an elongated chamber providing a lower melting space and an upper combustion space, with a series of inlet openings for the latter proximate its forward top wall; in combination with means associated with said inlet openings for projecting a series of blast flames across said upper space toward its rear wall, to allow for the complete combustion of said flames before striking the fusing mass in the lower space, the top and 25 rear walls of said combustion space serving to divert and direct the continuing resultant blasts of deoxidized heat forwardly across the melting mass in suffused intimate contact therewith; and exhausting flues leading from the lower portion of said chamber, through said front wall, and coöperating in pairs at positions lying in vertical planes on the opposite sides of practically all of said inlet openings, substantially as described. 30
5. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 35
6. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 40
7. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 45
8. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 50
9. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 55
10. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 60
11. A reduction furnace, embodying an elongated chamber providing a lower melting space and an upper combustion space, and including a rear wall, a substantially higher front wall and an arched top wall curving downwardly from said front wall to said rear wall; a series of inlet openings being provided, through said front wall, proximate said arched top wall; in combination with means associated with said inlet openings for projecting a series of blast flames across the deflecting surface of said arched top wall; and exhausting flues leading from the lower portion of said chamber, through said front wall, and coöperating in pairs at positions lying in vertical planes on the opposite sides of practically all of said inlet openings, substantially as described. 65

In testimony whereof, I affix my signature.

THEODORE W. MUCKLE.
